(57) **CLAIM**

The ornamental design of the lattice panel having opposed wavy pattern, as shown and described above.

DESCRIPTION

FIG. 1 is a elevational view of a front side of the lattice panel having opposed wavy pattern of the new design.

FIG. 2 is a elevational view of a back side, opposite the front side of the lattice panel having opposed wavy pattern of FIG. 1.

FIG. 3 is an edge view of one edge the lattice panel having opposed wavy pattern of FIGS. 1 and 2, and the view of the opposite edge is a mirror image of this view.

FIG. 4 is a top view of the lattice panel having opposed wavy pattern of FIGS. 1-3.

FIG. 5 is a bottom view of the lattice panel having opposed wavy pattern of FIGS. 1-4.

FIG. 6 is a perspective view of the front side of the lattice panel of FIGS. 1-5; and,

FIG. 7 is a perspective view of the back side of the lattice panel of FIGS. 1-6.
